United States Patent Office

Des. 181,366
Patented Nov. 5, 1957

181,366

STORAGE RACK

Benjamin F. Miller, Darien, Conn., assignor to Artistic Wire Products Company, Incorporated, East Hampton, Conn., a corporation of Connecticut

Application December 4, 1956, Serial No. 44,063

Term of patent 14 years

(Cl. D44—29)

Fig. 1.

Fig. 2.

Fig. 3.

Fig. 1 is a front elevational view of a storage rack, showing my new design.

Fig. 2 is an end view thereof.

Fig. 3 is an isometric view of said rack.

I claim:

The ornamental design for a storage rack, as shown.
